UNITED STATES PATENT OFFICE.

BEN M. HAMLIN, OF CHICAGO, ILLINOIS, ASSIGNOR TO J. V. MEYERING TRUNK COMPANY, OF CHICAGO, ILLINOIS, A CORPORATION OF ILLINOIS.

WARDROBE TRUNK.

Application filed November 28, 1919. Serial No. 341,134.

To all whom it may concern:

Be it known that I, BEN M. HAMLIN, a citizen of the United States, and a resident of Chicago, Cook County, and State of Illinois, have invented certain new and useful Improvements in Wardrobe Trunks, of which the following is declared to be a full, clear, and exact description.

This invention relates to trunks and more particularly to that type of trunks commonly called wardrobe trunks. Trunks of this character are usually constructed of two sections hinged together on a vertical axis, one of the sections ordinarily being provided with drawers and other compartments, and the other section being provided with a fixture and garment hangers. A follower is provided in the garment section, and ordinarily the follower serves merely for the one purpose of holding the garments in compact form so that they will not become disturbed and wrinkled from the rough use to which trunks are put, but may retain their shape while suspended in the garment section of the trunk.

One object of this invention is to provide an ironing-board which is suspended in the hanger-section of the trunk and which is capable of being adjusted to horizontal, ironing position with its outer-end propped up by a prop and its inner-end supported upon the two side-walls of the hanger-section, to thereby utilize said side-walls virtually as two separated legs and thus provide a broad, substantial support for the board while functioning as an ironing-board.

Another object of this invention is to provide a follower or retainer having the usual function of holding the clothing in a compact mass and also the alternative function of an ironing-board, means being provided whereby the follower-board when not used as a follower may be adjusted so as to project outwardly from the open side of the trunk and be propped up in a horizontal, ironing position, the side-walls of the hanger-section serving as leg-supports for the board.

Another object of the present invention is to provide a follower which may be readily converted into an ironing board, supported in horizontal position by the trunk and by the brace or locking bar, which

is used for holding the follower in place against the garments. Another object is to provide a follower which may be adjustably held in the garment section of the trunk so as to accommodate a few or a large number of garments, and which may be readily converted into an ironing board supported in horizontal position by the trunk and the means that are used to press it against the garments.

Another object is to provide a convertible follower capable of use as an ironing board and having a removable prop for supporting it upon the surface supporting the trunk, which prop is arranged to be used as the means for securing the follower in place against the garments when used for its original purpose.

With these and other objects and advantages in view, this invention consists in a follower for wardrobe trunks arranged to be converted into an ironing board having means for supporting it in horizontal position. It further consists in a follower for wardrobe trunks arranged to be converted into an ironing board having a prop for supporting its free end and adapted to be used as the means for securing the follower in place against the garments supported in the trunk. The invention further consists in the several novel features hereinafter fully set forth and claimed.

The invention is clearly illustrated in the drawings accompanying this specification, in which:

Fig. 1 is a perspective view of a wardrobe trunk shown in open position and equipped with a convertible follower containing a simple embodiment of the present invention; Fig. 2 is a front elevation of the garment section of the trunk, showing the follower in front elevation; Fig. 3 is a horizontal section taken on the line 3—3 of Fig. 2; Fig. 4 is a rear elevation of the follower locking bar, showing the same in extended position when used as a prop for the ironing board; Fig. 5 is a detail side elevation of fragments of the ironing board and prop; Fig. 6 is a detail horizontal section through the ironing board, and Fig. 7 is a fragmental detail vertical section taken on the line 7—7 of Fig. 3.

Referring to said drawings, the reference character 10 designates the garment section

and 11 the drawer section of a wardrobe trunk A, of ordinary and well known construction. Preferably the garment section 10 is provided with a top 12 hinged to one side *a* of the garment section whereby it may be swung upward to expose the upper end of said section. Locking mechanism of any suitable form may be provided for securing the cover down upon the garment section and for locking the two sections together. In the upper end of the garment section is supported a garment supporting fixture B, which has the usual horizontal rods 13 that support the garment hangers 14. The parts thus far described are common and well known and need no further description so far as this specification is concerned.

In the form of the invention chosen for the purpose of illustration, the follower C comprises a flat member 15 preferably in the form of a board, to one end of which is secured a rod 16, which supports one end of the board and is detachably secured to the garment section of the trunk, by any suitable means. In the drawings, a pair of notched bars or racks 17 are shown secured on the inner faces of the sides *a* of the garment section 10, which notched bars or racks receive the ends of the rod 16, the latter being provided, as a preference, with heads 18 upon its ends that prevent accidental disengagement with the notched bars. Means are provided for holding the board 15 in contact with the garments supported by the hangers 14, and as shown said means comprise a locking bar 19 and two perforated, serrated or notched brackets 20 secured to the inner face of the sides *a* of the trunk section 10, the locking bar 19 being provided with co-operating lock or latch mechanism adapted for engagement with said brackets 20. As a preference, a hook like member 21 may be provided on one end of the bar 19, which may be inserted in any one of the holes in one of the brackets 20 and the other end of the bar may be provided with a latch 22 having a spring pressed bolt for engagement in the holes of the other bracket 20. The base plate of the latch 22 is formed with a hook 22^a that hooks over the bracket 20. (See Fig. 7.) The bar 19 when placed against the follower board 15 and when engaged with the brackets 20 holds the follower from swinging outward, and by placing the rod 16 of the follower in the proper notches in the notched bars 17 and swinging the follower board 15 tightly against the garments, the bar 19 may be secured to the brackets 20 in position against the board so as to securely hold it in firm, pressing engagement against the garments.

The follower thus far described may be readily disconnected from the garment section of the trunk by drawing back the

spring bolt of the latch 22, swinging forward the bar 19 and withdrawing the hook like member 21 from the hole in the bracket 20, after which the board 15 may be raised to disconnect the rod 16 from the notched bars 17.

To use the follower board 15 as an ironing board, I have padded one side thereof as at 23 (see Fig. 6), and have covered the board and padding with a covering 24. The follower board may be used as an ironing board by swinging it up into horizontal position, with one end supported by the notched bars 17, the other end may be supported in any suitable manner, but I have made use of the locking bar 19 for this purpose, and have made said bar in two sections 25, 26 hinged together by a hinge 27, whereby the two sections may be extended to form a prop twice the length of one section. The hinge 25 is located on the side of the prop opposite the side on which the latch is located and clips 30 are pivotally secured to the section 25 by two of the rivets that fasten the latch to the section 25 and have end portions that are arranged to be swung over the section 26 when the two sections 25, 26 are extended to form a prop. Said clips 30 then engage with the underside of offset portions of clips 31 secured to the section 26 of the prop. This arrangement prevents buckling of the hinged prop when extended. A clip 32, having offset portions, is secured to the section 25 in position to hold the clips 30 in place when not in use. The board 15 is provided with a ring or loop 28, which is secured to the board by a clip 29, with which ring the hook like member 21 of the locking bar 19 is made to engage when the locking bar is used as a prop to support the free end of the board 15 in horizontal position.

In use, the follower is removed from the garment section of the trunk, garments hung upon the hangers 14 and the latter placed upon the garment supporting fixture. The hangers are then pushed back toward the rear of the garment section, the rod 16 of the follower placed on the notched bars 17 close to the hangers, and the padded side of follower board swung down against the clothes. The locking bar 19, which has been folded back on its hinge 27, is then secured upon the brackets 20 to hold the follower board in firm contact with the garments by inserting the hook 21 into one of the holes in the bracket 20 on the left side of the section, and the other end of the locking bar then brought into engagement with the opposite bracket 20 and pushed back until the locking bar holds the board 15 in firm contact with the garments, the spring bolt of the latch 22 entering one of the adjacent holes in the bracket 20. It will be observed that the hooks 21, 22^a engage with the brackets 20 and effectually prevent the lock-

ing bar from becoming disconnected therefrom in the event that the trunk is handled roughly. Furthermore, when the cover 12 is brought down upon the top of the garment section of the trunk, it is impossible for the hangers to become disengaged from the fixture B or for the rod 16 of the follower board to be disengaged from the notched bars 17. The trunk is closed and 10 locked in the usual manner.

To use the follower as an ironing board, the locking bar 19 is disconnected from the brackets 20, the two sections 25, 26 swung into alignment, and the clips 30 swung under the off-set ends of the clip 31, thus making a rigid prop of the two sections of the locking bar. The follower board 15 may then be moved into horizontal position, with the padded side up, and the rod 16 thereof 20 placed in any of the notches of the notched bars 17. The hook 21 of the extended follower locking bar 19 is then hooked in the ring or loop 28 and the prop swung down bringing its upper end into engagement 25 with the underside of the board. The garment section of the trunk is thereby made to act as a support for one end of the ironing board, and the unfolded or extended locking bar is thus made to act as a prop or leg 30 for the other end of the ironing board, said prop resting upon the floor or other surface supporting the trunk. When not in use the prop may be disconnected from the ring 28 of the ironing board, the ironing board permitted to swing down into 35 the garment section of the trunk, the clips 30 swung out of engagement with the off-set ends of the clip 31 and the two sections 25, 26 of the locking bar swung together 40 ready to be fastened to the brackets 20 to hold the board 15 in position as a follower.

More or less variation of the exact details of construction is possible without departing from the spirit of this invention; I desire, therefore, not to limit myself to the 45 exact form of the construction shown and described, but intend, in the following claims, to point out all of the invention disclosed herein.

I claim as new, and desire to secure by Letters Patent:

1. In combination with a wardrobe trunk, a clothes retainer or follower in the form of a removable and reversible ironing-board 55 padded on one side, means being provided for holding the padded side of said follower in clamping engagement with the clothing and said follower being provided at its upper-end with laterally-projecting members, 60 and means on the hanger-section of the trunk for interlocking with said members when the follower is reversed and adjusted to horizontal position for ironing purposes to thereby hold the follower against lateral

displacement and to utilize the hanger-section as a support for the board. 65

2. In a wardrobe trunk having a section which contains a garment hanger fixture and garment hangers supported thereby, a follower supported by said section and having 70 a locking bar for holding the follower in operative, upright position, said follower capable of being converted into an ironing board supported at one end by said section and at the other end by said locking bar. 75

3. In a wardrobe trunk having a section which contains a garment hanger fixture and garment hangers supported thereby, a follower supported by said section having an extensible locking bar for holding said 80 follower in upright, operative position, said follower capable of being converted into an ironing board supported at one end by said trunk section and supported at the other end by the extended locking bar resting on the 85 surface supporting the trunk.

4. In a wardrobe trunk having a section which contains a garment hanger fixture and garment hangers supported thereby, a follower comprising a flat member and 90 means for clamping said flat member in said section in upright, operative position, said means being also arranged to support said flat member in horizontal position whereby the latter may be used as an ironing board. 95

5. In a wardrobe trunk having a section containing a garment fixture and garment hangers supported thereby, a pair of oppositely disposed notched bars secured to the top of said section, a follower board having 100 a supporting rod detachably secured in opposing notches of said notched bars, an extensible locking bar and brackets on said section for holding said board in upright, operative position, said locking bar when 105 extended operating as a prop supporting the free end of said board in horizontal position, whereby it may be used as an ironing board.

6. In a wardrobe trunk having a garment 110 section containing a garment fixture and garment hangers supported thereby, a follower board removably supported by said section, an extensible locking bar and brackets for holding said board in upright, operative position, said locking bar having a detachable connection with the free end of said board and capable of acting as a prop to support said free end when the board occupies a horizontal position, whereby the 120 latter may be used as an ironing board.

7. In a wardrobe trunk having a garment section containing a garment fixture and garment hangers supported thereby, a follower board removably supported by said section, an extensible locking bar and brackets for holding said board in upright, operative position, said locking bar having 125

- means for holding it in extended position and having a detachable connection with the free end of said board and capable of acting as a prop to support said free end when the board occupies a horizontal position, whereby the latter may be used as an ironing board.
8. In a wardrobe trunk having a garment section containing a garment fixture and 10 garment hangers supported thereby, a follower board removably supported by said section, brackets secured to said section, an extensible locking bar having hooks engaging said brackets to lock said board in upright-operative position, and a loop on the free end of said board, one of the hooks on said locking bar being adapted for engagement with said loop to detachably connect the extended locking bar with said board 20 when the latter occupies a horizontal position, whereby the same may be used as an ironing board.
9. In a wardrobe trunk having a garment section containing a garment fixture and 25 garment hangers supported thereby, a follower board removably supported by said section, an extensible locking bar and brackets for holding said board in upright, operative position, said locking bar having bracket engaging means, means for holding the bar in extended position, and a detachable connection with the free end of said board and capable of acting as a prop to support said free end when the board occupies a horizontal 35 position, whereby the latter may be used as an ironing board.
10. In combination with a wardrobe trunk, a follower and means for clamping it against the clothing, said follower being a padded 40 ironing-board, and cooperating means between the two side-walls of the hanger-section of the trunk and one end of the board for supporting said board in a horizontal position, the opposite end of said board being provided with means for engaging a support for the outer end of the board.
11. A wardrobe trunk having garment hangers supported therein, a follower support, and a combined follower and ironing 50 board supported in said trunk by said follower support, means being provided adjacent one end for supporting said board in a substantially horizontal position said board being supported in ironing position at the 55 other end by the trunk follower support.
12. In combination with a wardrobe trunk, a combined ironing board and follower, means on the trunk to suspend said combined ironing board and follower in the 60 trunk in upright position to act as a follower and also to support the said combined ironing board and follower at one end when in ironing position and means to support the opposite end of the said combined ironing 65 board and follower.
13. In combination with a wardrobe trunk, a combined ironing board and follower, a transverse rod at one end thereof, means on the trunk engaging said rod to support the said combined ironing board and follower 70 at one end when in ironing position as well as in follower position and means to support the opposite end of the said combined ironing board and follower.
14. The combination with a wardrobe 75 trunk having a clothes-hanger section including clothes-hangers, of a follower in the form of an ironing-board, means for pivotally suspending said follower and for clamping it against the clothing carried 80 by the hangers, said pivotally-suspending means permitting the board to be swung outwardly and upwardly to horizontal position so as to function as an ironing-board.
15. In a wardrobe trunk having a hanger 85 section provided with suspended adjustable hangers, a solid follower in the form of an ironing-board and means for adjustably suspending said board within the hanger section, means for clamping the board against 90 the clothing in the hanger section, said suspending means embodying a pair of oppositely-projecting pivots which serve as a support for the inner-end of the board when it is adjusted to horizontal position to function 95 as an ironing-board.
16. In a wardrobe trunk embodying two hinged sections, one of which is a clothes-hanger section containing a plurality of adjustable hangers, a solid follower in the form 100 of an ironing-board and means for adjustably suspending it within the hanger section, said means embodying a pair of oppositely-projecting pivots adapted to act as supports for the board both while functioning as a follower and while functioning as 105 an ironing-board, and means for clamping the follower-board against the clothes on the hangers.
17. A wardrobe trunk provided with ironing-board-supports arranged to support a follower at various places, garment hangers for suspending garments therein, a follower in the form of an ironing board removably supported by said supports and movable 115 from front to back in said trunk, and means for holding said follower in compressive engagement with garments suspended in the trunk, said follower having a supporting member coacting with said ironing-board-supports on the trunk to secure one end of the follower in horizontal position when serving as an ironing board.
18. A wardrobe trunk embodying a drawer-section and a clothes-hanger-section 125 hinged together, the vertical walls of the clothes-hanger-section being provided at their upper outer corners each with a supporting-bracket, an ironing-board having lateral supporting members at its inner end 130

removably engaging said supporting-brackets in such manner as to permit the board to hang vertically thereon within the hanger-section when the trunk is closed and to 5 permit the board to be adjusted to horizontal position outside the hanger-section for ironing purposes when the trunk is open, whereby when in the latter position the two vertical walls of the trunk virtually form 10 two legs for the inner end of the ironing-board, and a movable prop for the outer end of the ironing-board when in ironing position.

19. A wardrobe trunk comprising two sections adapted to open apart, one section being an open clothes-hanger-section, an ironing-board pivotally supported on the vertical walls of the clothes-hanger-section at 15 their upper outer corners, whereby the ironing-board may hang in a vertical position within the hanger-section when the trunk is closed and may swing up to horizontal position when the trunk is open, the vertical walls of the hanger-section serving as two 20 legs when the board is thus adjusted to horizontal position for ironing purposes, and a prop for the outer end of the ironing-board.

20. A wardrobe trunk embodying two hinged sections, the front of one of said sections being open, a bracket affixed to the inside of each vertical side-wall of this open section near its upper outer corner, an ironing-board and means attached to its inner end for engagement with said brackets to 30 permit the board to hang vertically within the hanger-section when the trunk is closed or to be adjusted to horizontal position for ironing purposes when the trunk is open, said means embodying abutments to prevent end- 35 wise movement of the supporting means in the brackets, and a prop for the outer end of the board when in ironing position.

21. A wardrobe trunk comprising two hinged sections one of which is open at the 45 front side, brackets affixed to the vertical side-walls of the open section on the inside thereof, an ironing-board having a rod attached to its inner edge and projecting beyond the side edges of the board, said projecting ends being adapted to pivotally engage in said brackets to permit the board to 50 pivotally hang vertically within the trunk or to swing up to a horizontal position outside the trunk for ironing purposes, said 55 projecting ends having lateral shoulders to engage the said brackets and thus tie the walls of the trunk together and at the same

time prevent lateral movement of the board in the brackets, and a prop for the outer end of the board when in ironing position. 60

22. In a wardrobe trunk embodying a hanger-section having adjustable clothes-hangers therein, a follower in the form of an ironing-board and devices for adjusting and locking the board against the clothing 65 on the hangers to thereby clamp the same in a compact mass, said board being provided at each end with means for engaging a support when the board is used as an ironing-board, the means at the upper-end of the 70 follower-board being adapted to engage and be supported on the two side-walls of the hanger-section, said two side-walls being provided with devices adapted to interlock with said means and thus hold the follower-board against lateral movement while in use 75 as an ironing-board.

23. In a wardrobe trunk embodying a plurality of suspended adjustable clothes-hangers and a follower and means for 80 clamping said follower against the clothing on the hangers, said follower being in the form of a padded solid board adapted to serve as an ironing-board when removed from the hanger-chamber of the trunk, said 85 follower being provided at its inner, upper end with means whereby it will be pivotally suspended when in use as a follower and be supported on the two side-walls of the hanger-section when adjusted for ironing 90 purposes, said two side-walls of the hanger-section being provided with brackets for engaging and supporting the means on the inner, upper end of the follower.

24. In a wardrobe trunk having a hanger-section, adjustable clothes-hangers in said hanger-section, a presser adjustably hung in said hanger-section, and means whereby said presser may be maintained in pressure relation to the clothes on said hangers, said 100 presser being a stiff, flat board in the form of a padded ironing-board and being provided at its inner, upper end with means whereby it may be supported on the trunk structure when adjusted for use as an ironing-board, the hanger-section of the trunk being provided on its two side-walls with 105 interlocking devices cooperating with said means on the follower to thereby utilize the side-walls as supports and also hold the follower against lateral movement while in use 110 as an ironing-board.

BEN M. HAMLIN.
